Patent Engineering Corporation, a corporation
of Delaware

Application April 16, 1932. Serial No. 605,568

12 Claims. (Cl. 179—1)

This invention relates to improvements in speaker amplifiers and has for an object the provision of means for effecting regeneration at audio frequencies.

5 Another object of the invention is to generate a series of impulses by means of the motion of a moving part of a loud speaker.

A further object of the invention is to superimpose generated impulses directly controlled by 10 the motion of a loud speaker, upon the same amplifier which furnishes the original impulses, thereby obtaining a gain in the volume of sound reproduced by the speaker.

Other objects and advantages of the invention 15 will be apparent to those skilled in the art.

In loud speaker systems where a large volume of sound is required it has heretofore been necessary to provide powerful amplifiers for use therewith utilizing larger and more costly tubes and 20 the portability of such amplifiers is limited due to the size thereof and the weight of the elements therein.

In the present invention, an ordinary amplifier is used and a crystal is provided and driven by 25 a moving part of the speaker and the voltage generated by the crystal (due to the flexing thereof) is fed back into the amplifier and the amplified voltage impulses are thereby impressed upon the speaker along with the signal impulses. This 30 causes the speaker to vibrate with still greater motion (and sound) thereby generating greater motion and hence higher voltage impulses in the crystal and so on until a maximum volume of sound is obtained, effecting an audio frequency 35 regeneration in the amplifier. This is accomplished with smaller elements in the amplifier unit for the same output than heretofore.

Referring to the drawings:

Figure 1 is a side elevation of a loud speaker 40 comprising one embodiment of the invention;

Figure 2 is a section of the device in Figure 1 along the line 2—2; and

Figure 3 is a circuit suitable for use with the device and showing one method of connecting 45 the crystal to the amplifier portion of the circuit.

In one embodiment of the invention a dynamic speaker is shown but it is obvious that any type of speaker may be used.

This speaker designated by the numeral 10 has 50 a field coil 11 supported on a suitable frame 12.

An annular ring 13 carried by the frame 12 serves as a support for the outer edge of the cone 14.

A voice coil 15 is secured to or made integral 55 with the smaller end of the cone and is thereby

held within the magnetic field of the field coil 11.

A flexible arm 16 is also secured to the cone adjacent to the voice coil 15 and is secured to a boss 17 on the frame 12 in any suitable manner such as by a screw 18.

A crystal 19 which may be of any material having piezo-electric qualities such as quartz or rochelle salt, etc. has metallic sheets or plates 20 and 21 secured to the sides thereof and connected to the lead wires 22 and 23 respectively.

A clamp bracket 24 is rigidly secured to one end of the crystal 19 and is mounted on the frame 12 by means of screws or rivets 25.

A second bracket 26 is clamped to the other end of the crystal 19 and an extended arm 27 thereof is secured to the flexible arm 16 by a rivet 28 or any other suitable means.

When the loud speaker is operated the flexible arm 16 vibrates and at the same time the motion of the arm 16 is imparted to the end of the crystal 19 via the clamp bracket 26. Since the other end of the crystal has its clamp 24 rigidly secured to the frame 12 the crystal 19 is flexed and a voltage is generated, the impulses thereof being in time relation to the movement of the moving element 80 of the loud speaker.

By superimposing this voltage upon the input of the amplifier portion of a radio receiver an increase in output is obtained giving a regenerative effect.

A diagram showing connections for obtaining 85 this effect is shown in Figure 3 in which the elements are shown conventionally.

The cone 14 with its attached voice coil 15 under the influence of the field 11 are shown, and 90 the crystal 19 is moved by the moving part of the speaker.

The lead 22 is connected to ground and the lead 23 is connected via a condenser 31 to the input of the first audio frequency amplifier tube 30, thereby the impulses generated by the crystal 19 are superimposed upon the control element 32, amplified by the first stage 33 and further amplified by the push-pull stage 34.

This addition of the superimposed impulses to 100 the primary impulses or signals rectified by the detector 29 and passing through the amplifier 30, 34 causes still greater movement of the moving element of the speaker, causing greater voltages to be generated by the crystal 19 and these greater impulses passing through the amplifier giving a regenerative effect and a substantial increase in the volume of the speaker is effected 105 without the necessity of additional electronic stages in the amplifier.

While a simple embodiment of the invention is herein shown and described it is obvious that many changes may be made without departing from the scope of the invention as defined in the 5 following claims.

What is claimed is:

1. The herein described method of effecting regeneration which consists of amplifying signals in an electron tube amplifier, reproducing 10 the amplified signals by means of a loud speaker, flexing a fixed piezo-electric crystal by the movement of said speaker thereby causing the crystal to generate electrical impulses in timed relation to said signals, and passing said impulses through 15 said amplifier along with the signals passing therethrough.
2. A loud speaker comprising a moving element and means for vibrating the same, and a fixed piezo-electric crystal separate from said means 20 associated with said speaker and adapted to be flexed by the movement of said speaker.
3. A loud speaker comprising a frame, a moving element and means for vibrating the same mounted on said frame, and a crystal separate 25 from said moving element having one end rigidly secured to said frame and the other end operationally connected to a moving part of said speaker and adapted to move therewith.
4. A loud speaker having a frame and a moving element adapted to reproduce signals, means for moving said element and a crystal supported by said frame and driven by said element adapted 30 to generate impulses in timed relation to the movement of said element, said crystal being separate from said means.
5. A loud speaker having a frame, a moving element carried by said frame, a stationary element mounted on the frame for moving said first element, and a crystal separate from said stationary element having one end rigidly secured to the frame and its other end driven by the moving 40 element.
6. A loud speaker having a frame, a moving element carried by said frame, a stationary element mounted on the frame for moving said first element, an arm having one end secured to the moving element and the other end secured to the frame, and a crystal separate from said stationary element having one end rigidly secured to the frame and the other end secured to said arm.
7. A loud speaker having a frame, a moving element carried by said frame, a stationary element mounted on the frame for moving said first element, a flexible arm having one end secured 50
- to and adapted to be flexed by the moving element and the other end secured to the frame, and a crystal separate from said stationary element having one end rigidly secured to the frame and the other end adapted to be moved synchronously 55 with the flexing of said arm.
8. In combination a magnetic device having a frame, a crystal having a portion rigidly fixed to said frame and having a portion adapted to be flexed by said magnetic device, and means for amplifying impulses generated by said crystal due to the flexing thereof. 85
9. In combination an amplifier, a magnetic device having a frame connected thereto, a crystal having a portion rigidly fixed to said frame and having a portion adapted to be flexed by said device, and means connecting said crystal to the input end of said amplifier whereby impulses generated by said crystal due to the flexing thereof are amplified along with signals 90 passing therethrough and regeneration is effected. 95
10. In combination an amplifier, a loud speaker connected to said amplifier, a piezo-electric crystal adapted to be moved by said speaker when actuated by signals passing through said amplifier, and means for superimposing impulses generated by said crystal upon signals entering said amplifier, whereby a regenerative action is attained and all signals entering said amplifier are 100 amplified therein in proportion to the movement of said crystal.
11. In combination an amplifier having input and output stages, a loud speaker connected to said output stage, a signal translating device 110 connected to the input stage, a crystal adapted to be flexed by movement of said speaker, and means connecting said crystal to said input stage, whereby a regenerative action is attained and all signals entering said amplifier are amplified 115 therein in proportion to the movement of said crystal.
12. In combination an amplifier having a plurality of electronic stages including input and output stages, a loud speaker connected to said output stage, a signal translating device connected to the input stage, a crystal adapted to be flexed by movement of said speaker, and means connecting said crystal to one of said stages, whereby a regenerative action is attained and all signals 120 entering said amplifier are amplified therein in proportion to the movement of said crystal. 125
